(57) **CLAIM**

The ornamental design for a bolt with stepped head, as shown and described.

DESCRIPTION

FIG. 1 is a representative front elevation view showing the new design, the left, right and rear elevation views being the same;

FIG. 2 is a top plan view thereof;

FIG. 3 is a bottom plan view thereof;

FIG. 4 is a top isometric view thereof.

FIGS. 5-9 are views of a second embodiment wherein:

FIG. 5 is a front elevation view thereof, the rear view being a mirror image;

FIG. 6 is a left side elevation view thereof, the right side view being a mirror image;;

FIG. 7 is a top plan view thereof, and

FIG. 8 is a bottom plan view thereof; and,

FIG. 9 is a top isometric view thereof.
